UNITED STATES PATENT OFFICE

CHARLES ALGERNON PARSONS AND FREDERICK ARKLESS, OF NEWCASTLE-ON-TYNE,
ENGLAND; SAID ARKLESS ASSIGNOR TO SAID PARSONS

SURFACE CONDENSER

Application filed June 22, 1929, Serial No. 372,963, and in Great Britain June 22, 1928.

The main object of the present invention is to provide an improved form of surface condenser of comparatively simple construction and high efficiency.

With such an object, the present invention consists in a condenser with nests of tubes, in which the steam enters at the top and is guided to the bottom through a central baffled duct or through laterally-disposed baffled ducts to ascend through the nests of tubes by way of a gradually diminishing area.

Referring to the accompanying diagrammatic drawings:-

Figure 1 is a cross-section through one form of the condenser taken on the line 1—1 of Figure 2;

Figure 2 is a corresponding longitudinal section taken on the line 2—2 of Figure 1, and

Figure 3 an elevation of the condenser and turbine exhausting thereinto; while finally

Figures 4, 5 and 6 are corresponding views of a modified form of condenser applied to a double-flow turbine.

When not otherwise mentioned, the same reference symbols are used in the different figures to denote corresponding parts.

In carrying the invention into effect according to one form, (see Figures 1, 2 and 3) the condenser, 2, receives the exhaust from a turbine, 3, by way of a duct, 4, and takes the form of a cylinder of oval cross-section with its major axis horizontal; the

casing or shell is preferably constructed of steel plates with the necessary stiffeners and so forth while the condenser tubes are disposed in a horizontal position in two main groups, 5a, 5b, one on each side of the condenser, each group being connected at each

end to separate water boxes, (see for example, 6, 7, Figure 2) provided with the appropriate inlet and outlet circulating water connections, 6a, 6b, on one side and 8a, 8b,

45 on the other side (Figure 3) and doors, 6c, 8c.

The two main groups of tubes, 5a, 5b, are spaced apart (see Figure 1) to leave a central duct, 9, along the length of the condenser passing from the steam inlet, 10, at

the top to the bottom part of the shell. Longitudinal baffles, 11a, 11b, defining the transverse dimensions of the upper part of the central duct are arranged one on each side of the vertical centre line of the condenser, the upper parts of these baffles being a distance apart substantially corresponding to the transverse dimensions of the steam inlet 10, while the baffles approach each other towards the centre of the condenser. (See Figure 1.) The lower part of each nest of tubes is or may be curved away from the central duct as shown at 12a, 12b, to allow free access of the steam to the lower tubes. As the steam enters, therefore, it spreads out longitudinally to fill the duct between the two baffles, and by way of the central duct sweeps outwardly below the baffles to pass upwards through the tubes, the cross-sectional area available for flow diminishing towards the air suction connections, 13a, 13b, provided on each side of the condenser at the top in proximity to its relative baffle.

The condensate is extracted at the bottom of the condenser through any usual outlet, 14, which may be protected by a hood, 15. (See Figure 1.)

The condenser as a whole is preferably supported on suitable resilient supports indicated at 16a, 16b.

The baffles, 11a, 11b, which form the sides of the duct, 9, through which the steam flows downwards between the nests of tubes, also serve to protect the tubes from erosion such as occurs in condensers in which the top rows of tubes are exposed to the direct action of water thrown off the turbine blading at high velocity.

The condensate falling through the tube nests towards the water extraction branch, 14, has to pass through the steam stream so that the condenser works on what is commonly known as the régenerative principle.

Further, as the two nests of tubes, 5a, 5b, one on each side, are provided with separate doors 6c, 8c, preferably of approximately semi-circular shape to correspond with the cross section of the condenser, cleaning of the condenser tubes may be carried out without

shutting down the whole plant by shutting off the circulating water from the half of the condenser to be cleaned and opening or removing the door of the corresponding water box to expose the tubes. During this process condensation continues in the other half of the condenser.

According to a modified form of the invention, (see Figures 4, 5 and 6) the same main features are embodied in the condenser but in a modified manner, the two nests of tubes, 5a, 5b, being placed closer together while the single central duct, 9, is replaced by two ducts, 9a, 9b, arranged one on each side of the condenser, which they envelop on the sides and bottom, the upper part of each such duct being provided with a steam inlet, 10a, 10b, respectively.

Baffles are arranged between the tubes and the steam inlets, 10a, 10b, and in the present modification take the form of longitudinal partitions, 15a, 15b, extending outwardly and downwardly from the top of the condenser on each side to about its mid depth. (See Figure 4.)

As before, air is withdrawn at the top of the condenser while one or more fittings for the pump suctions are provided at the bottom.

Such a modified form of the invention is particularly applicable to a double-flow turbine, 17, (see Figure 5) with exhaust ducts, 4a, 4b, one at each end, the two laterally-disposed condenser inlets, 10a, 10b, above described being spaced apart to correspond with the turbine outlets, 4a, 4b.

Alternatively, in any form of the invention a section of the tube nests may be disposed in the steam inlet ducts 9, 9a, 9b, so that the downward steam stream scrubs over these tubes and is partially condensed thereon.

The constructions described are applicable to a condenser with any number of water flows.

Various modifications may be made in the details of construction of the condensers described without exceeding the scope of the invention.

We claim:

1. A surface condenser comprising in combination, a casing having an inlet through the upper part thereof for the medium to be condensed, said inlet leading to a free space within said casing running longitudinally for substantially the whole length thereof, condensing tubes within said casing also running longitudinally thereof, and baffle means of a depth less than the depth of said casing depending from the upper part thereof, said baffle means being disposed within said casing between said free space and said tubes, so that the medium to be condensed sweeps round the entire lower edge of said baffle means and attacks said tubes along their whole length.

2. A condenser as claimed in claim 1, in which said tubes are arranged in a plurality of symmetrical nests with baffling means operatively disposed in relation to each of said nests.

3. A condenser as claimed in claim 1, having a plurality of nests of tubes within said casing with said free space between the upper parts thereof, said baffling means being disposed between said free space and said nests of tubes on the two sides thereof.

4. A condenser as claimed in claim 1, having a plurality of nests of tubes within said casing with said free space between the upper parts thereof, said baffling means being disposed between said free space and said nests of tubes on the two sides thereof and mutually converging in the downward direction.

5. A condenser as claimed in claim 1, in which said tubes are arranged centrally in said casing in a plurality of juxtaposed nests with the baffling means operatively disposed between said nests and the wall of said casing.

6. A condenser as claimed in claim 1, in which said tubes are arranged centrally in said casing in a plurality of juxtaposed nests with the baffling means operatively disposed between said nests and the wall of said casing and forming therewith steam ducts contracting in a downward direction.

In testimony whereof we have signed our names to this specification.

CHARLES ALGERNON PARSONS.
FREDERICK ARKLESS.
